TIME-DELAYED UNDERVOLTAGE TRIPPING-MECHANISM FOR CIRCUIT BREAKERS

John W. May, Pittsburgh, Pa., assignor to Westinghouse Electric & Manufacturing Company, East Pittsburgh, Pa., a corporation of Pennsylvania

Application May 9, 1940, Serial No. 334,182

6 Claims. (Cl. 200—108)

My invention relates to time-delayed undervoltage tripping-mechanisms for circuit-breakers, and it has particular relation to such devices utilizing a suction-type or sucker-type dashpot in combination with a clapper-type undervoltage electromagnet.

An object of my invention is to provide a novel lost-motion connecting-means between the movable armature-arm of the electromagnet and the plunger of the dashpot in order to obtain proper action of both the dashpot and the electromagnet, without the necessity for exact niceties in the design, and bearing in mind the necessity for avoiding any lateral or twisting reactions on the stem of the dashpot-plunger, and recognizing the fact that both the dashpot-plunger and the electromagnet-armature must be seated securely on their respective frames, in order to develop the intended forces.

While my invention was designed particularly for utilization in connection with air-type circuit-breakers, and while it is so illustrated in the accompanying drawings, I wish it to be understood that the invention, in its broader aspects, is not limited to any particular type of circuit-breaker.

In the drawings:

Figure 1 is a sectional side-elevational view, not precisely to scale, but showing the general principles of an illustrative kind of circuit-breaker and circuit-breaker operating-mechanism, embodying a preferred form of embodiment of my improved undervoltage mechanism, the section-plane being approximately indicated by the line I—I in Fig. 2, and the operating-handle having been removed.

Fig. 2 is a front-elevational view of a 3-pole breaker embodying my invention.

Fig. 3 is a cross-sectional view on approximately the plane indicated by the line III—III in Fig. 2, showing a side elevation of my improved undervoltage mechanism, the drawings being not precisely to scale, but illustrating the general principles of my improved mechanism, and

Fig. 4 is a front-elevational view of the undervoltage mechanism shown in Fig. 3.

My invention is illustrated in connection with an air-type circuit breaker which is illustrated as being mounted upon an insulating panel 5 and comprising two main stationary contact-members 6 and 7 (Fig. 1) which are bridged by a movable contact-member 8 carried by a movable contact-arm 9 which is pivoted at 11 on a stationary frame-member 12 (Figs. 1 and 2) carried

by the panel 5. The main contacts 6—8—7 are supplemented by auxiliary contacts 13 (Fig. 1) and also by arcing-contacts 14, associated with an arc-chute structure which is diagrammatically indicated at 15 (Figs. 1 and 2). The particular circuit-breaker which I have illustrated utilizes a contact-system which is described and claimed in a patent of Leon R. Ludwig and Merl E. Horn, No. 2,144,471, granted September 10, 1940, and assigned to the Westinghouse Electric & Manufacturing Company; while the illustrated arc-extinguishing structure 15 may be that which is described and claimed in an application of Leon R. Ludwig, Serial No. 216,884, filed July 1, 1938, and assigned to the Westinghouse Electric & Manufacturing Company, which application became Patent No. 2,243,038 on May 20, 1941.

In Fig. 1, I have illustrated a circuit-breaker mechanism which is substantially that which is described and claimed in an Austin Patent No. 2,177,014, granted October 24, 1939.

As shown in Fig. 1, the movable contact-arm 9 is normally biased toward an open position by means of an accelerating or opening spring 16, which is connected between a point 17 on the breaker-arm 9 and a point 18 on the frame 12. The movable contact-arm 9 of the breaker is also connected, by means of a pivoted link 20, to a pin 21 carried by a toggle-lever 22 (Figs. 1 and 2).

The toggle-lever 22 is pivoted on a stationary pivot 23 (Fig. 1) carried by the frame 12, and it is shaped and arranged so as to carry two other pivot-pins 24 and 25, in addition to pivot-pin 21, as well as having two depressions or spring-seats 26 and 27, a cam-surface 28, and an attachment-point 29 for an opening-spring or accelerating-spring 31, the other end of which is connected to a fixed pivot 32 carried by the frame 12. The toggle-lever 22 may also be provided with an air bumper 33, as illustrated.

The toggle-lever 22 is operatively associated with a closing lever 34 (Figs. 1 and 2) which is independently pivoted upon the same stationary pivot 23 (Fig. 1). The closing lever 34 carries a pin 35 which is provided with a roller 36 (Fig. 1); and it is also connected to a cross-bar 37 (Figs. 1, 2 and 3) which extends transversely across the breaker-mechanism.

The toggle-lever 22 and the closing lever 34 are adapted to be releasably held together or interlocked, by means of a trigger latch 38 (Fig. 1) which is carried by the pivot-pin 25 on the toggle-lever 22. The front end of the trigger

latch 38 is provided with a latching surface 39 which abuts against the roller 36 of the closing lever 34, and the rear end of the trigger latch 38 carries a roller 41 which is normally latched or engaged by the end 42 of a roller trigger 43. The roller trigger 43 is carried by the pivot-pin 24 of the toggle-lever 22 and is provided with a depending arm 44 which may be actuated in order to trip or release the roller trigger 43 from the roller 41 of the trigger latch 38. When the trigger-latch 38 is in its latched position, as shown in Fig. 1, it operatively ties the toggle-lever 22 to the closing lever 34 so that they will be held together.

The closing lever 34 is normally retained in its illustrated closed position, that is, when the circuit-breaker is closed, by means of a trigger or other releasable holding-means 45 which is pivotally carried by the stationary pivot 32, and which is provided with a shoulder 46 which engages the roller 36 of the closing lever 34, so as to prevent the latter from opening. The trigger 45 is also provided with a cam-surface 47 which is adapted to be engaged by the cam surface 28 of the toggle-lever 22 when the toggle-lever opens, as will be subsequently described, thus releasing the trigger-shoulder 46 from its engagement with the roller 36 of the closing lever 34.

The release of the roller trigger 43 is effected by means of a tripping lever 50 (Fig. 1) which is carried by the stationary pivot-pin 32. The tripping lever 50 is provided with a shoulder 51 which is adapted to engage the depending arm 44 of the roller trigger 43 so as to actuate said roller trigger against the bias of a spring 52 which is seated in the depression 26 of the toggle-lever 22. The actuation of the roller trigger 43 lifts its abutment-end 42 out of engagement with the roller 41 of the trigger latch 38, so that the force of the powerful opening-spring 31 of the toggle-lever 22 will operate on the trigger latch 38 along a line joining the pivot-pin 25 with the abutment-end 39 of the trigger latch, this line of action being slightly off-center with respect to the line joining the pivot-pins 25 and 35, so that the trigger latch 38 will be kicked off of the roller 36 of the closing lever 34 as soon as its own roller 41 is released by the roller trigger 43. The trigger latch 38 is provided with a light relatching-spring 53 which is seated in the depression 27 in the toggle-lever 22.

The tripping lever 50 and the trigger 45 are joined by means of a spring 54 which serves to bias the trigger 45 toward its latching position, with its latching-shoulder 46 in engagement with the roller 36 of the closing lever 34. The spring 54 also biases the tripping lever 50 toward its non-tripping position in engagement with a spring-stop 55. The tripping lever 50 is provided, at one end, with a transversely extending actuating arm 56 (Figs. 1 and 3), while its other end is connected to a trip-bar 57 (Figs. 1 and 2).

The bottom stationary contact-member 7 (Fig. 1) is connected in series with a series trip-coil 58 which is operative, when the current reaches a predetermined magnitude, to elevate an armature 59 carrying a trip-pin 60 which engages the actuating arm 56 of the tripping lever 50, so as to elevate the tripping shoulder 51 into engagement with the depending arm 44 of the roller trigger 43, so as to release the trigger latch 38.

The circuit-breaker contact-structure and operating-mechanism thus far described is usually a part of a multiple-pole construction such as is shown in Fig. 2, wherein a 3-pole breaker is 75

shown, with the different poles separated by barriers 61 and 62. Each pole is provided with its own toggle-lever 22 and closing lever 34, together with the necessary latching means therefor, but the cross-bar 37 is common to all three poles, and the trip-bar 57 is also common to all three poles. The cross-bar 37 of Fig. 2 is provided with a closing-handle or operating-handle 63. A common trip-handle 64 may be provided on the trip-bar 57, as indicated in Fig. 2.

My improved undervoltage mechanism is disposed at the right-hand end of the circuit-breaker as viewed in Fig. 2. It is shown in detail in Figs. 3 and 4. Essentially, it is a time-delayed drop-out clapper-type electromagnet or controlling-means which is adapted to drop out to a non-actuated position when the electromagnetic force developed therein falls below a predetermined minimum value. It is illustrated as comprising a U-shaped electromagnet-frame 66, the back of which is mounted on the panel 5. One leg of the electromagnet-frame 66 is provided with a coil 67 for normally energizing the undervoltage mechanism in accordance with a predetermined response to a predetermined voltage, 20 usually the voltage of the line to which the circuit-breaker is connected. The two legs or pole-pieces of the electromagnet-frame 66 are adapted to be bridged by a movable armature 68 which is carried by a main lever or movable armature-arm 69 which is pivoted on a fixed pivot 71 carried by an extension of the electromagnet frame 66.

The main lever or movable armature-arm 69, 35 besides carrying the magnetizable armature 68, is provided with a lug 73 carrying a pin 74 to which a biasing-spring 75 is connected, the other end of the biasing-spring being secured at a point 76 on an extension of the electromagnet-frame 66 in such position that the line of action of the spring, between the points 74 and 76, is slightly below the center of the main-lever pivot 71, in the seated position of the armature 68, so that the biasing-spring 75 develops a relatively 40 weak biasing-moment, tending to turn the movable armature-arm 69 clockwise, in an opening or dropping-out direction, as long as the armature 68 is seated against the pole-faces or abutments of the electromagnet-frame 66, said biasing force increasing rapidly in magnitude as the armature 68 moves away from the electromagnet frame 66, thus causing the armature-arm 69 to fly open rapidly, when once its opening movement is started by a full or material separation of the armature 68 from the pole-face portions of the electromagnet-frame 66. This biasing force can be adjusted by means of a vertical adjustment of the fixed spring-fastening 76, as indicated at 77.

The main lever or movable armature-arm 69, 55 in addition to carrying the armature 68 and the spring-terminal 74, is also provided with a shoulder 78, an upwardly bent arm 79, and a downwardly extending arm 80. The upwardly bent arm 79 is connected, by means of a pivoted link 82, to an undervoltage trip-lever 83 which is pivoted on a fixed pivot 84 carried by the electromagnet-frame 66. The undervoltage trip-lever 83 is provided with an adjustable bumper or projection 85 which is adapted to engage the laterally extending actuating arm or cross-piece 56 of the circuit-breaker tripping lever 50 to elevate the latter in response to the flying-open movement of the armature-arm 69.

Means are provided for automatically retriev-

ing the armature 68, or returning it to its seated position in engagement with the electromagnet-frame 66, in response to an opening movement of certain parts of the circuit-breaker mechanism. This armature-retrieving means includes a reset-lever 87 which is pivoted on the fixed pivot 71. The reset-lever 87 is provided with a shoulder 88 which is adapted, at times, to abut against the shoulder 78 of the movable armature-arm 69. The reset-lever 87 is also provided with an upwardly extending arm-portion 90 which carries a terminal-connection 91 of a strong resetting-spring 92, the other end of which is carried by a fixed point 93 in an extension of the electromagnet-frame 66. The effect of the resetting-spring 92 is to strongly bias the reset-lever 87 in a clockwise, or resetting, direction, so that, if the resetting-spring 92 has its way, it will force the reset-shoulder 88 against the armature-arm shoulder 78 with a force strong enough to reset or reseat the armature 68 against the bias of its opening or drop-out spring 75.

The reset-lever 87 is also provided with an outwardly extending arm 95 which carries a pivot-pin 96 to which is attached a substantially vertical link 97 terminating in a pin 98 which rises in a substantially vertical slot 99 in a bracket 100 carried by the cross-bar 37 of the closing levers 34 of the circuit-breaker mechanism. Whenever the circuit-breaker is in its closed position, the linkage-pin 98 rests in the top of the slot 99 and causes the vertical link 97 to press the reset arm 95 downwardly, so as to hold the reset shoulder 88 out of engagement with the movable armature-arm 69 of the undervoltage tripping-mechanism, leaving the movable armature-arm 69 free to fly open when the forces operating upon the armature-arm have a suitable resultant component in the opening direction.

After the circuit-breaker has tripped to an open-circuiting position of its movable contact-arm 9 (Fig. 1), and before the movable contact-arm can be reclosed, the closing lever 34 will be moved in an opening direction in which the cross-bar 37 is elevated, this operation being performed either automatically or, as illustrated, by an elevation of the handle 63 (Fig. 2). The vertical link 97 and the slotted bracket 100 of the undervoltage-mechanism (Fig. 3) constitute a lost-motion mechanical coupling-means for the reset-lever 87 whereby, when the cross-bar 37 begins to move upwardly, in its opening movement, the reset-lever 87 at first moves with it, under the impulse of its resetting-spring 92, so as to forcibly or mechanically return the movable armature-arm 69 to its closed position in which the armature 68 is properly seated upon the pole-pieces of the electromagnet-frame 66. The lost-motion-coupling means is such, however, that after the armature 68 has been seated, so that the resetting-spring 92 can no longer move the reset-lever 87 in the counterclockwise or resetting direction, the cross-bar 37 of the closing levers 34 (Fig. 1) may still continue through the final portion of its opening movement, during which time the linkage-pin 98 slides down through the slot 99 of the bracket 100, or rather the bracket 100 continues to move upwardly while the linkage-pin 98 remains still.

When the cross-bar 37 of the reclosing levers 34 is forced downwardly, during the closing movement of the actuating-mechanism of the circuit-breaker, it at first has a loose connection with the undervoltage-mechanism, while the

linkage-pin 98 rises in the slot 99, but the final closing-movement of the breaker-mechanism forces the reset-lever 87 downwardly, so that its shoulder 88 moves away from the cooperating shoulder 78 on the movable armature-arm 69, during the last portion of the closing-movement of the breaker-mechanism, it being contemplated that the electromagnet-coil 67 of the undervoltage-mechanism will meanwhile have been energized, so that the electromagnetically developed force will hold the armature 68 in engagement with the electromagnet-frame 66 when the reset-lever 87 moves out of engagement with the armature-arm 69.

15 The above-described mechanical resetting of the armature 68 is necessary, because a clapper-type undervoltage magnet or relay, such as I utilize, does not usually develop a sufficient electromagnetic pull, under normal excitation-conditions, to attract the armature 68 to the electromagnet-frame 66 except when the armature is close to the pole-pieces of the frame.

In accordance with my invention, as shown in Fig. 3, the bottom depending arm 80 of the movable armature-arm 69 of the undervoltage-responsive mechanism is cooperatively associated with a dashpot 102 which operates as a time-delay means for delaying the early stages of the opening movement of the armature-arm 69. The dashpot itself is of the suction-type in which the bottom surface of a movable plunger 103 is adapted to be normally seated in substantially contacting-engagement with the stationary top surface of the bottom member 104 of the dashpot, the dashpot being preferably partially filled with oil 105. As a result of this construction, a substantial force is required, which must be maintained for a certain predetermined interval of time, in order to separate the seating surfaces 103 and 104. The dashpot usually embodies means for adjusting the operating-force and the time of operation. This adjusting means may be of any desired type, but has nothing to do with my present invention, a desirable means to that end being shown, however, in the Austin Patent No. 1,578,572, granted March 30, 1926.

In accordance with my invention, a novel loose-connection means is also utilized for the operative connection between the vertical plunger-rod 106 of the dashpot and the depending end 80 of the movable armature-arm 69 of the undervoltage-magnet. The upper end of the plunger-rod 106 is provided with a pivot-pin 107 carrying a roller 108 which is adapted to be engaged by the upper end-surface 109 of the main-lever arm 66 when the main lever or armature-arm 69 moves a very slight amount away from the fully seated engagement of the armature 68 with the electromagnet-frame 66. In accordance with my invention, the upper surface 109 of said depending arm 80 is so shaped that it reacts in a substantially exactly vertical direction against the roller 108 carried by the plunger-rod 106, or in a direction which is substantially normal, or at right angles, to the substantially contacting suction-surfaces 108—109. This provision is made, because any slight lateral force, or rocking movement, applied to the movable plunger-member 103 of the dashpot, introduces a serious variation in the time-delay setting or operation of the dashpot.

In accordance with my invention, I have provided loose-connection means whereby both the electromagnet-armature 66 and the dashpot-plunger 103 may be seated, against their respec-

tive contacting surfaces, with a slight lost-motion between them, so that it is not necessary to so finely adjust the manufacturing tolerances of the apparatus that both of these parts will become seated at the same instant during the resetting movement of the electromagnet-mechanism.

In the particular form of my invention which is illustrated in Figs. 3 and 4, the bottom surface 111 of the depending end 89 of the armature-arm 69 moves downwardly, during the closing or resetting movement of the armature-arm 69, and in the very last stage of this closing-movement, it presses against the top of a slidable sleeve 112 on the plunger-rod 106 and forces said slidable sleeve downwardly so as to compress a spring 113 which is disposed between said slidable sleeve 112 and a fixed collar 114 on the plunger-rod 106.

The result of the foregoing design is that the final movement of the armature-arm 69, in the closing direction, depresses the bottom end of the arm 80 a slight distance down below the lifting-roller 108 of the plunger-rod 106, so as to provide a loose-connection means such that, when the armature 68 is seated, the two substantially contacting suction-surfaces 103 and 104 are yieldably pressed together by the spring 113. On the other hand, when a predetermined reduction in the applied voltage or current in the magnet-coil 67 causes the biasing-spring 75 to begin to move the armature-arm 69 a very slight amount away from the full seated engagement of the armature 68 on the electromagnet-frame 66, the slight initial separation between the surface 109 and the roller 108 will be taken up, so that the suction between the substantially contacting surfaces 103 and 104 of the dashpot will restrain any further or substantial opening-movement of the armature arm 69 until the suction-action is substantially broken at the suction-surfaces 103 and 104.

The object of this time-delay action, which prevents the armature 68 from becoming substantially or materially separated from its electromagnet-frame 66 for a certain time-delay determined by the dashpot, is to render the undervoltage-mechanism unresponsive to voltage-dips of momentary or predeterminedly brief duration by temporarily holding the armature 68 so close to the electromagnet-frame 66 that the electromagnetic pull will be able to grip the armature upon the restoration of normal voltage-conditions. Thus, the circuit breaker will not be unnecessarily tripped open, in response to voltage-drops of such brief duration as to be unimportant from an operational standpoint with respect to the electrical system in which the circuit breaker is connected.

While I have described my invention in combination with a certain type of circuit-breaker and a certain type of operating-mechanism therefor, and while I have described certain details of the undervoltage relay or magnet, and the dashpot, and the mechanical connecting-means between the undervoltage armature-arm 69 and both the dashpot and the operating-mechanism of the circuit-breaker, and while I at present consider the illustrated form of embodiment of my invention to be a preferred form, I wish it to be understood that such illustration is only illustrative, and that various changes may be made without departing from the essential spirit of my invention, at least in its broader aspects. I desire, therefore, that the appended claims shall be accorded the broadest construction consistent with their language.

I claim as my invention:

1. A time-delayed drop-out mechanism comprising a clapper-type electromagnet having an electromagnet-frame and a movable armature-arm having a frame-engaging armature-portion, means for biasing said armature-arm toward an open position in opposition to the electromagnetic attraction, time-delay means for delaying the early stages of the opening-movement of the armature-arm, said time-delay means comprising a suction-type dashpot having relatively stationary and relatively movable normally-seated and substantially-contacting suction-surfaces, and loose-connection means connecting the movable element of said dashpot with said movable armature-arm in such manner that, when the armature-portion of the armature-arm is released by its electromagnet-frame, the loose-connection of the loose-connection means permits the armature-arm to move substantially unimpededly a very slight amount away from its seated engagement with the electromagnet-frame, whereupon the movable element of the dashpot restrains the further movement of said armature-arm until the suction-action is substantially broken at said suction-surfaces, after which the dashpot permits the armature-arm to again move substantially unimpededly whereby the armature-arm effects a rapid flying-open movement in the rest of its opening-movement away from the electromagnet-frame.
2. A time-delayed drop-out mechanism comprising a clapper-type electromagnet having an electromagnet-frame and a movable armature-arm having a frame-engaging armature-portion, means for biasing said armature-arm toward an open position in opposition to the electromagnetic attraction, time-delay means for delaying the early stages of the opening-movement of the armature-arm, said time-delay means comprising a suction-type dashpot having relatively stationary and relatively movable normally-seated and substantially-contacting suction-surfaces, a movable-element stem attached to said relatively movable suction-surface member and having a substantially rectilinear movement in a line at substantially right angles to said suction-surfaces, and loose-connection means connecting the movable-element stem of said dashpot with said movable armature-arm in such manner that, when the armature-portion of the armature-arm is seated against its electromagnet-frame, the loose-connection means transmits a force from the electromagnet to the dashpot whereby the two substantially contacting suction-surfaces are pressed together, the loose-connection of the loose-connection means permitting the armature-arm to move substantially unimpededly a very slight amount away from its seated engagement with the electromagnet-frame, whereupon the movable element of the dashpot restrains the further movement of said armature-arm until the suction-action is substantially broken at said suction-surfaces, after which the dashpot permits the armature-arm to again move substantially unimpededly whereby the armature-arm effects a rapid flying-open movement in the rest of its opening-movement away from the electromagnet-frame, the loose-connection means between the armature-arm and the stem being such as to produce substantially no force-reaction on the stem in any direction other than the aforesaid line of movement thereof during the suction-operation of said dashpot.

3. A time-delayed drop-out mechanism comprising a clapper-type electromagnet having an electromagnet-frame and a movable armature-arm having a frame-engaging armature-portion, means for biasing said armature-arm toward an open position in opposition to the electromagnetic attraction, time-delay means for delaying the early stages of the opening-movement of the armature-arm, said time-delay means comprising a suction-type dashpot having relatively stationary and relatively movable normally-seated and substantially-contacting suction-surfaces, and yieldable loose-connection means connecting the movable element of said dashpot with said movable armature-arm in such manner that, when the armature-portion of the armature-arm is seated against its electromagnet-frame, the loose-connection means transmits a force from the electromagnet to the dashpot whereby there is a relatively small resilient reaction between the armature-arm and the movable element of the dashpot yieldably pressing said suction-surfaces together, the loose-connection of the loose-connection means permitting the armature-arm to move substantially unimpededly a very slight amount away from its seated engagement with the electromagnet-frame, whereupon the movable element of the dashpot restrains the further movement of said armature-arm until the suction action is substantially broken, after which the dashpot permits the armature-arm to again move substantially unimpededly whereby the armature-arm effects a rapid flying-open movement in the rest of its opening-movement away from the electromagnet-frame.

4. Tripping-means for releasing the holding-means of the mechanism of a circuit-breaker, comprising the combination, with said breaker, of a time-delayed undervoltage-responsive mechanism comprising a clapper-type electromagnet having an electromagnet-frame and a movable armature-arm having a frame-engaging armature-portion, means for biasing said armature-arm toward an open position in opposition to the electromagnetic attraction, means for causing the flying-open movement of the armature-arm to effect the release of said holding-means, time-delay means for delaying the early stages of the opening-movement of the armature-arm, said time-delay means comprising a suction-type dashpot having relatively stationary and relatively movable normally-seated and substantially-contacting suction-surfaces, and loose-connection means connecting the movable element of said dashpot with said movable armature-arm in such manner that, when the armature-portion of the armature-arm is released by its electromagnet-frame, the loose-connection of the loose-connection means permits the armature-arm to move substantially unimpededly a very slight amount away from its seated engagement with the electromagnet-frame, whereupon the movable element of the dashpot restrains the further movement of said armature-arm until the suction-action is substantially broken at said suction-surfaces, after which the dashpot permits the armature-arm to again move substantially unimpededly whereby the armature-arm effects a rapid flying-open movement in the rest of its opening-movement away from the electromagnet-frame.

5. Tripping-means for releasing the holding-means of the mechanism of a circuit-breaker, comprising the combination, with said breaker, of a time-delayed under-voltage-responsive mech-

anism comprising a clapper-type electromagnet having an electromagnet-frame and a movable armature-arm having a frame-engaging armature-portion, means for biasing said armature-arm toward an open position in opposition to the electromagnetic attraction, means for causing the flying-open movement of the armature-arm to effect the release of said holding-means, time-delay means for delaying the early stages of the opening-movement of the armature-arm, said time-delay means comprising a suction-type dashpot having relatively stationary and relatively movable normally-seated and substantially-contacting suction-surfaces, a movable-element stem attached to said relatively movable suction-surface member and having a substantially rectilinear movement in a line at substantially right angles to said suction-surfaces, and loose-connection means connecting the movable-element stem of said dashpot with said movable armature-arm in such manner that, when the armature-portion of the armature-arm is seated against its electromagnet-frame, the loose-connection means transmits a force from the electromagnet to the dashpot whereby the two substantially contacting suction-surfaces are pressed together, the loose-connection of the loose-connection means permitting the armature-arm to move substantially unimpededly a very slight amount away from its seated engagement with the electromagnet-frame, whereupon the movable element of the dashpot restrains the further movement of said armature-arm until the suction-action is substantially broken at said suction-surfaces, after which the dashpot permits the armature-arm to again move substantially unimpededly whereby the armature-arm effects a rapid flying-open movement in the rest of its opening-movement away from the electromagnet-frame, the loose-connection means between the armature-arm and the stem being such as to produce substantially no force-reaction on the stem in any direction other than the aforesaid line of movement thereof during the suction-operation of said dashpot.

6. Tripping-means for releasing the holding-means of the mechanism of a circuit-breaker, comprising the combination, with said breaker, of a time-delayed undervoltage-responsive mechanism comprising a clapper-type electromagnet having an electromagnet-frame and a movable armature-arm having a frame-engaging armature-portion, means for biasing said armature-arm toward an open position in opposition to the electromagnetic attraction, means for causing the flying-open movement of the armature-arm to effect the release of said holding-means, time-delay means for delaying the early stages of the opening-movement of the armature-arm, said time-delay means comprising a suction-type dashpot having relatively stationary and relatively movable normally-seated and substantially-contacting suction-surfaces, and yieldable loose-connection means connecting the movable element of said dashpot with said movable armature-arm in such manner that, when the armature-portion of the armature-arm is seated against its electromagnet-frame, the loose-connection means transmits a force from the electromagnet to the dashpot whereby there is a relatively small resilient reaction between the armature-arm and the movable element of the dashpot yieldably pressing said suction-surfaces together, the loose-connection of the loose-connection means permitting the armature-arm to

move substantially unimpededly a very slight amount away from its seated engagement with the electromagnet-frame, whereupon the movable element of the dashpot restrains the further movement of said armature-arm until the suction-action is substantially broken at said suction-surfaces, after which the dashpot permits

the armature-arm to again move substantially unimpededly whereby the armature-arm effects a rapid flying-open movement in the rest of its opening-movement away from the electromagnet-frame.

JOHN W. MAY.
